PACKAGE

Shy Rosen, Chicago, Ill., assignor to Milprint Products Corporation, Milwaukee, Wis., a corporation of Wisconsin

Application February 11, 1932. Serial No. 592,369

11 Claims. (Cl. 206—46)

My invention relates to an improved display wrapper package for food commodities such as sliced bacon and the like.

One of the objects of my invention is to provide a novel package or wrapper for food commodities, such as sliced bacon, which are characteristically limp and irregular in form and difficult to handle and wrap in a manner which will properly display them and at the same time completely enclose and protect them.

Other objects of my invention will appear hereinafter.

The accompanying drawings illustrate my invention as embodied in several modifications of packaging forms or wrappers.

Fig. 1 is a plan view illustrating my improved wrapper laid out flat with a quantity of sliced bacon placed in position thereon ready to be wrapped;

Fig. 2 is a longitudinal section on the line 2—2 of Fig. 1, showing the end flaps or extended portions folded onto the food product to be wrapped;

Fig. 3 is a transverse section on line 3—3 of Fig. 1, illustrating the wrapper partly formed around the food product;

Fig. 4 is a transverse section of a completed package;

Fig. 5 is a face view of a completed package of modified form;

Fig. 6 is a flat view of the character of Fig. 1, but illustrating the form of package of Fig. 5;

Fig. 7 is a longitudinal section on line 7—7 of Fig. 6;

Fig. 8 is a transverse section of the completed package of Fig. 5;

Fig. 9 is a flat view like Fig. 1, of still another modification;

Fig. 10 is a longitudinal section on line 10—10 of Fig. 9;

Fig. 11 is a transverse section of a completed package formed of the wrapper structure of Fig. 9; and

Fig. 12 is a face view of the completed package of the Fig. 9 type.

It is desirable in wrapping food or other articles that a substantial portion thereof be exposed through the wrapper for display purposes, and for this reason I utilize a thin flexible sheet of suitable transparent wrapping material 1 such as cellophane, for the display portion of the wrapper, which in the completed package exposes a substantial portion of the article to view. In fact, with my improved wrapper, practically the whole area of one side or face of the completed package is formed by the transparent portion 1 of the wrapper. The flexible sheet of cellophane is preferably rectangular and is somewhat longer and wider than the article 2 to be wrapped, so that the portions which project beyond the ends 60 of the article form end flaps 3 which are folded

over the ends of the article as shown more particularly in the sectional view Fig. 2. The sheet of cellophane is laid out flat and the article 2, such as the group of slices of bacon, placed thereon in the central portion thereof. While wrapping the article the cellophane sheet is laid flat on a table and is on the bottom of the package, but when the package is completed and turned over, the cellophane portion becomes the top or display side of the package.

In the form shown in Figs. 1 to 4, there are provided two rectangular strips or sheets 4 and 5 of relatively stiff material such as cardboard which provides stiffness or rigidity and regularity of form to the completed package. These strips 75 in the form shown in Figs. 1 to 4 are separate pieces, but in the modifications in Figs. 5 to 12 they are cut from a single sheet of material and connected by integral cross-connecting portions, as will be hereinafter described.

These strips are preferably rectangular in shape and are preferably made substantially the length and width desired for the completed package because, in a sense, they determine these dimensions when the wrapper is folded around the article. In the manufacture of the wrapper, these stiff backing strips are positioned to overlap the longitudinal marginal portions 6 of the cellophane sheet in parallel relation to the edges thereof, the overlapping portions of the cellophane and stiff members being secured together by glue or any suitable adhesive. The edges 7 of the two strips are spaced apart on the cellophane sheet substantially the width desired for the completed package because these edges determine the lines 90 along which the sheet 1 is folded in wrapping the article.

The manufactured wrapper comes to the operator as a flat structure comprising the cellophane sheet 1 with the strips or flap members 4 and 5 attached as above described. The operator lays one of these wrappers on the table in flat condition and places on the central portion thereof the slices of bacon or other article to be wrapped. The operator first folds the end flaps 3 of the transparent sheet over the end portions of the article, as indicated in Fig. 2, using the end edges 9 of the strips 4 and 5 to define the lines on which the folds of the flaps are made. After the end folds have been formed, the stiff flap members 4 and 5 are folded over the top of the article, first one and then the other in superposed relation, the folds in the sheet 1 being defined by the edges 7 of said stiff members 4 and 5, as shown in Fig. 4. The folding of these flaps completes the enclosure of the food product in a package which completely protects the contained product.

The edges 7 and 9 of the backing flaps 4 and 5 are in definite spaced relation, hence the fold- 120

ing of the wrapper on the lines of these edges acts to always form a uniform package of the same definite width and length without the exercise of any particular skill on the part of the operator. This is obvious because whether the folding is done manually or by means of folding mechanism, the relatively stiff edges 7 and 9 automatically cause the fold to take place on these lines.

- 10 In the event that the food article should extend beyond the area defined by the folding lines, the folding of the flaps will force or compress the article within the dimensions of the package. Thus a neat appearing package is always formed.
- 15 The package is stiffened by the two layers of cardboard flaps 4 and 5 so that it can be handled as much as necessary and still retain its shape. The flaps 4 and 5 are preferably not sealed so that a portion of the contents can be removed
- 20 and the remaining portion again wrapped by refolding the flaps.

It is desirable in a package of this character, to display the goods to the best advantage and for this reason it is desirable that the transparent portion of the wrapper, which constitutes the window for exposing the goods, shall lay smooth and unruffled. In my improved package this is accomplished very effectively in the folding of the wrapper for the reason that the package has no definite side faces but, in effect, has simply a front or top transparent face and a bottom or rear non-transparent face. On account of the thickness of the article, however, the flexible transparent portion of the wrapper is forced into curved formation. The backing flaps or members 4 and 5, being relatively stiff, are not curved in section to any great extent. Hence, when the flaps are folded, the curving of the cellophane causes it to tension or stretch transversely and this action lays the cellophane material flatly against and in intimate contact with the surface of the contained article. In the case of sliced bacon or similar products which are wet or greasy, the cellophane material adheres intimately to the article and because of its transparency it does not show, but the food article appears in a natural uncovered condition. In this manner the character of the product is very effectively displayed. In addition to this, the pressing of the meat or other product into intimate contact with the cellophane excludes air from the exposed face of the meat and preserves this exposed face against deterioration for a relatively long period of time thereby maintaining the fresh and attractive appearance of the meat as it was originally packed.

While the stiff backing flanges 4 and 5 may be maintained in flat condition in the package, it is preferable that these members spring slightly out of a flat plane in the completed package in order to improve its appearance and form. Several score marks 13, spaced apart and arranged parallel longitudinally of the package may be provided in the faces of the stiff members 65 whereby in the folding of the flaps they will bend slightly along these score marks as indicated in Figure 4.

The outer faces of the stiff backing flaps 4 and 5 provide space upon which advertising matter may be placed, but it is desirable that a label of some character be provided on the display face of the package. In the structure shown in Fig. 1, this may be accomplished by the provision of a separate thin label 12 indicated in

75 dotted lines. The label may be placed trans-

versely upon the surface of the cellophane material before the bacon is placed thereon. When the wrapper is folded up, this label will also be stretched tightly across the displayed face of the product and will appear through the cellophane material when the package is completed.

The structures disclosed in Figs. 5 to 12 differ from the structure of Figs. 1 to 4 just described, principally in the fact that the flap members 4 and 5 are connected by integral cross members. This has an advantage over the structure of Fig. 1, particularly in the manufacturing of the wrapper for the reason that the cross-connecting members tie the two side flaps together and enable them to be die-cut from a single sheet of material, and in the assembling operation enables one piece of cardboard material to be handled instead of two separate flap members.

In the structure shown in Figs. 5 to 8, this cross member 14 is preferably transversely positioned midway of the length of the package and provided with suitable area upon which advertising matter such as the name of the manufacturer may be placed. This advertising matter 15 may be printed directly on the cross-connecting member 14 or a separate label may be attached to this member during the process of assembling the wrapper.

In the structure shown in Figs. 9 to 12, there is provided, in addition to the central cross member 14, end connecting portions 16 which are likewise formed integrally with the flap members. These end connecting portions together with the marginal portions 17 of the flap members have the effect of providing a window frame 110 on the display side of the package. In order that the marginal portion 17 will remain on the display face of the package when the wrapper is formed, the flaps are made wider and provided with score lines 18 for folding purposes. The score lines 18 correspond to the marginal edges 7 of the structure of Fig. 1 in determining the lines on which the flaps will be folded. Thus, when the wrapper is folded in the same manner as that described in connection with Fig. 1, the window-framing remains on the display face of the package as shown more clearly in Figs. 11 and 12. The flaps 4 and 5 in other respects function in the same manner in forming the back of the package. The advantage of this structure over that of either Figs. 1 to 4 or 5 to 8 lies in the fact that the exposed portion of the product is set-off trimmed by a frame which conceals the appearance of the ragged edges, particularly at the ends of the contained product.

It is apparent from the disclosures herein made that the structures embodying my invention are capable of changes in the construction and operation of the parts without departing from the spirit of the invention, and I contemplate such changes as fairly fall within the scope of the appended claims.

I claim:

1. In a package wrapper for food products, the combination of a flexible sheet of transparent material forming one side of the package to expose the contents thereof and having relatively stiff flap members attached to opposite edges of said sheet and folded one upon the other in superposed relation upon the opposite side of the contents to form the opposite side of the package, said sheet of transparent material having at its ends portions extending beyond the ends of the relatively stiff flap members and folded about the product on the opposite side of
- 140
- 145
- 150

- the package and positioned between the product and the stiff flap members to hold said end portions in place.
2. In a package-forming wrapper for food products, the combination of a rectangular sheet of flexible transparent cellulose material adapted to form one side of the package and through which the contained food products are exposed to view, and having relatively stiff flap members of substantial width spaced apart and attached to said flexible sheet and adapted to be folded in superposed relation one upon the other to form the opposite side of said package, said stiff flap members being shorter in length than the flexible sheet, and end flap portions formed by the portions of said flexible sheet which extend beyond the ends of said stiff flap members, adapted to be folded over the end portions of the food products enclosed by the wrapper.
3. In a wrapper for enclosing food products, the combination of two relatively stiff members in superposed relation one upon the other on one side of the enclosed food product, and a sheet of relatively flexible transparent wrapping material secured to said relatively stiff members and extending from one of said stiff members to the other around the opposite side of the food product.
4. In a wrapper for enclosing food products, the combination of two relatively stiff members in superposed relation on one side of the enclosed food product, and a sheet of relatively flexible transparent wrapping material secured to said relatively stiff members and extending from one of said stiff members to the other around the opposite side of the food product and maintained taut by the food product between the stiff members and said transparent sheet, said sheet having end portions extending beyond the ends of said relatively stiff members and folded over the ends of the contained food product and held in place between the food product and the relatively stiff members.
5. In a package for enclosing food products, the combination of two relatively stiff members substantially the width of the package in superposed relation on one side of the enclosed food product, and a sheet of relatively flexible transparent wrapping material secured to said relatively stiff members and stretched from one stiff member to the other around the opposite side of the food product and maintained taut by the food product between the said stiff members and said transparent sheet.
6. In a wrapper for food products, the combination of a sheet of relatively flexible transparent material adapted to be disposed on one side of the article to be wrapped and having its end portions extended beyond the body of the article and folded to overlie the opposite side of said article at the ends thereof, parallelly disposed relatively stiff backing members attached to the sheet of flexible material and adapted to be folded from opposite sides of the sheet with one of said stiff members overlying the other and both of said members overlying the folded end portions of the sheet.
7. In a wrapper for food products, the combination of a sheet of relatively flexible transparent material adapted to be disposed on one side of the article to be wrapped and having its end portions extended beyond the body of the article and folded to overlie the opposite side of said article at the ends thereof, parallelly disposed relatively stiff backing members attached to the sheet of flexible material and adapted to be folded from opposite sides of the sheet with one of said stiff members overlying the other and both of said members overlying the folded end portions of the sheet.
- sheet of flexible material and adapted to be folded from opposite sides of the sheet with one of said stiff members overlying the other and both of said members overlying the folded end portions of the sheet, said stiff members, when thus folded, acting in cooperation with the wrapped article to tension the sheet of flexible material into intimate contact with the wrapped article.
8. In a wrapper for food products, the combination of a sheet of relatively flexible transparent material adapted to be disposed on one side of the article to be wrapped and having its end portions extended beyond the body of the article and folded to overlie the opposite side of said article at the ends thereof, parallelly disposed relatively stiff backing members attached to the sheet of flexible material and adapted to be folded from opposite sides of the sheet with one of said stiff members overlying the other and both of said members overlying the folded end portions of the sheet, and a cross member formed integrally with said relatively stiff members and extending from one to the other across the side of the article on which the relatively flexible material is disposed.
9. In a wrapper for food products, a sheet of relatively flexible transparent material and a window frame attached to said flexible material and disposed with the flexible material on one side of the wrapped article, relatively stiff flat members hinged to said frame and adapted to be folded upon the opposite side of the article in superposed relation, and extinctions of said flexible material extending beyond the ends of said frame and folded over the ends of the article to overlie the opposite side of the article between the article and the superposed stiff members.
10. In a wrapper for food products adapted to be folded about the article to be wrapped and comprising a pair of rectangular relatively stiff members substantially corresponding to the length and width of the article and disposed one upon the other on one side of the contained article, a sheet of transparent cellophane having its longitudinal marginal portions overlapping and secured to said stiff members and having end portions extending beyond the ends of said stiff members and folded on lines corresponding to said ends of said stiff members to overlie the opposite side of said article at the ends thereof, said cellophane extending around the side of said article opposite the stiff members and stretched into intimate contact with the article.
11. A wrapper for food products comprising a rectangular sheet of flexible transparent material adapted to be disposed against one side of the article to be enclosed and having end portions folded around the ends of the article to the opposite side thereof, a rectangular sheet of relatively stiff material secured to each longitudinal marginal portion of said flexible sheet so that the edges thereof determine the lines on which said flexible sheet folds, said flexible sheet being adapted to be folded on said lines to position the stiff members in overlying relation to each other on the opposite side of the article, said stiff members cooperating with the contained article to tension the flexible sheet between said stiff members so that the flexible sheet is pressed into intimate contact with the side of the article on which said sheet is disposed, said stiff members being shorter than the flexible sheet so that the end edges thereof define the line on which the extended end portions of the flexible sheet are folded.
- SHY ROSEN. 150
